UNITED STATES PATENT OFFICE.

HORACE G. JOHNSTON, OF CORSICANA, TEXAS, ASSIGNOR TO GENEVIEVE JOHNSTON,
OF CORSICANA, TEXAS.

ROTARY-DRILL HEAD.

1,348,117.

Specification of Letters Patent.

Patented July 27, 1920.

Application filed August 6, 1919. Serial No. 315,776.

To all whom it may concern:

Be it known that I, HORACE G. JOHNSTON, a citizen of the United States, residing at Corsicana, in the county of Navarro and State of Texas, have invented certain new and useful Improvements in Rotary-Drill Heads; and I do hereby declare the following to be a full, clear, and exact description of the invention, such as will enable others skilled in the art to which it appertains to make and use the same.

This invention relates to drill apparatus and more particularly to that type of apparatus in which drill rods of cruciform cross section are rotated while being sunk.

It is one of the objects of the present invention to improve the head gear or driving mechanism of drill apparatus and especially to provide for the efficient driving of the apparatus and yet enable the free vertical movement of the drill rod or driving shank.

With this and other objects in view, as will become readily manifest to those versed in the art, the invention consists in the means and in details and arrangement of the parts as more particularly described in the following specification relative to the embodiment of the invention shown in the accompanying drawing, wherein:

Figure 1 is a plan view of my improved driving head clamp.

Fig. 2 is a vertical section on a line 2—2 of Fig. 1.

Fig. 3 is a plan view of the head as mounted upon the turn table, and

Fig. 4 is a side elevation partially in section on a line 4—4 of Fig. 3.

The present apparatus is of that type involving a suitably rotated and horizontal table 2 driven by any suitable means, indicated here as including a pinion 3 engaging a complementary gear 4, formed or secured on the turn-table 2.

This turn-table is provided with a central bore or chamber in which there is mounted a removable bushing 5 which is free to rotate on a ledge 5^a on the turn-table and having lugs 6 which engage the under side 50 of the ledge on the interior surface of the turn-table 2.

On top of the turn-table are provided suitable bosses 8 cast integral with the turn-table on which are arranged suitable transverse fastening bars or cleats 10. The bosses

8 engage with recesses formed at the outer end of the clamp structure 13—13^a imparting rotary motion to the clamp.

An important feature of the present invention resides in the improvement of a clamp and the mounting of the same in the bushing or ring 5 and, as here shown, this ring is provided with a conical bore 11 complementary to the tapering body 12 of a clamp consisting of two substantially duplicate and interchangeable members 13 and 13^a which may be clamped together by transversely extending bolts 14.

This clamp constitutes, therefore, a split socket having a central longitudinal aperture 15, the transverse contour of which approximates the contour of the drill rod or shank that may be extended down through the head structure, such shank usually being longitudinally fluted or of cruciform cross section, so that its shoulders will interlock with the shoulders of the socket 15 and rotary motion therefore be imparted by the clamp to the drill rod or shank.

This rotary motion is transmitted in the present case from the driving dogs or bosses 8 which project into recesses formed in the outer end of the clamp structure 13—13^a and indicated at 16.

By the present construction the conical body part 12 of the clamp structure is designed to allow the bushing to rotate on it and also within the turn-table as may be necessary in the exigencies of operation, although the ring and the clamp may have a general rotation due to the rotation of the turn-table 2 which carries the driving means connecting the drill shank or rod to the driving head for rotation.

Having thus described my invention, what I claim is:

1. In a rotary drill operating mechanism, a turn-table having a central opening, a bushing rotatably mounted concentrically of said table, a clamp engaging means on the turn-table, a divided clamp adapted to be engaged by said clamp engaging means on the table, and means on the bushing for engaging said divided clamp to keep the same from spreading.

2. In a rotary drill operating mechanism, a turn-table having a central opening, a bushing rotatably seated in said opening and provided with means for preventing unseating thereof, a clamp engaging means

on the turn-table, a divided drill clamp adapted to be engaged by said clamp engaging means on the table, and coöperating means on said bushing and clamp to prevent 5 said clamp from spreading.

3. In a rotary drill head, a turn-table, a removable bushing free to rotate on a seat on the turn-table and having a conical seat, and a clamp removably mounted on the 10 seat and having a tapered body portion complementary to the bearing therefor on the bushing.

4. In a rotary drill head, a turn-table and its driving mechanism; a removable drill 15 receiving and driving clamp loosely mounted upon the turn-table, and having bifurcated ends; lugs on the turn-table to enter said

ends for driving purposes; and retaining means for preventing vertical or separating movement of the clamp and lugs.

5. In a rotary drill head, a turn-table and its driving mechanism; a removable drill receiving and driving clamp loosely mounted upon the turn-table, and having bifurcated ends; lugs on the turn-table to enter said 20 ends for driving purposes; and retaining means for preventing vertical or separating movement of the clamp and lugs, said last named means comprising transverse cleats secured to the lugs and overhanging the 25 clamp ends.

In testimony whereof I affix my signature.

HORACE G. JOHNSTON.
